B. W. KENDALL

REPEATER FOR MULTIPLEX SYSTEMS

Filed Oct. 31, 1919.

Inventor:
Burton W. Kendall.

by *J. G. Roberts* Atty.

UNITED STATES PATENT OFFICE.

BURTON W. KENDALL, OF NEW YORK, N. Y., ASSIGNOR TO WESTERN ELECTRIC COMPANY, INCORPORATED, OF NEW YORK, N. Y., A CORPORATION OF NEW YORK.

REPEATER FOR MULTIPLEX SYSTEMS.

Application filed October 31, 1919. Serial No. 334,681.

To all whom it may concern:

Be it known that I, BURTON W. KENDALL, a citizen of the United States, residing at New York, in the county of New York, State of New York, have invented certain new and useful Improvements in Repeaters for Multiplex Systems, of which the following is a full, clear, concise, and exact description.

10 This invention relates to multiplex signaling systems, and particularly to a repeater for such systems which is both simple and efficient. The invention is especially concerned with repeating a plurality of telephone conversations or telegraphic messages simultaneously, which several conversations or messages may be in the form of modulations of as many different carrier waves on a single transmission line. Broadly, however, the invention is not limited to signaling but is adapted for use in repeating for any purpose currents covering a large frequency-range.

Heretofore it has been thought necessary in order to repeat a plurality of carrier waves, each modulated in accordance with signals, to separate the several carrier waves and repeat the wave of each frequency by itself, afterward recombining the frequencies in the outgoing line. This procedure requires the use of considerable apparatus, including more or less complicated filters. According to the present invention all the frequencies that are being transmitted over the line in the same direction are repeated by a single repeater especially adapted for this purpose, and a two-way repeater may be provided by duplicating the circuit to provide a path for operation in the opposite direction.

A repeater suited to this use must have in effect a substantially linear characteristic throughout a considerable operating range, otherwise modulation of some of the currents by currents of other frequencies is liable to occur resulting in cross-talk or in other disturbances. According to the invention an amplifier commonly known as the "push-pull" type is arranged to serve as a repeater for all the waves simultaneously. A repeater of this type has the property of transmitting a plurality of frequencies separately and individually without producing their combination frequencies.

55 The drawing shows a schematic diagram

of a circuit according to a preferred embodiment of the invention.

In the drawing one terminal of a multiplex carrier current line is shown and a two-way repeater inserted at an intermediate point on the line. The opposite terminal of the line may be entirely similar to that shown. Two generators and modulators are shown for impressing currents on the line simultaneously for transmitting signals, and two receiving circuits are shown but it is to be understood that other transmitting sets and other receiving sets could be used in addition to those shown, by connecting them to the line in the manner indicated, and the invention is not limited to any particular number of such sets or to the particular type of transmitters or receivers that are used. Two line sections are indicated by 1, 2 and 3, 4 between which a plurality of conversation currents may be repeated simultaneously in each direction. Line section 1, 2 terminates at each end in line windings for the purpose of connecting to transmitting, receiving or repeating apparatus, and in the net circuits 5 and 6 respectively each of which simulates the characteristics of the line. Line windings 7 and 8 are inductively related to winding 9 through which currents are impressed on the line 1, 2 from generator-modulator sets T_1 and T_2 . The set T_1 comprises a generator 10 of any suitable type for producing an alternating current of carrier frequency (one) which may be a convenient value, preferably several thousand cycles, so as to be near or above the upper limits of audibility. Coupled to the generator is a modulator controlled by the microphone transmitter 12. The modulator shown is the well-known thermionic type consisting of an evacuated chamber in which are a cathode-filament 13, an anode 14 and a grid 15. A potentiometer resistance 16 with sliding contact enables the potential impressed on the grid 15 to be regulated. The normal potential of the grid is fixed relative to the filament by battery 17 and the batteries 18 and 19 are respectively for heating the filament 13 and furnishing space current. Current of carrier frequency (one) from generator 10 is normally repeated in amplified form by modulator 11 and impressed through condenser 20 to the tuned circuit 21, which is made resonant to this frequency and is

100 105 110

transmitted through the coupling shown to the secondary tuned circuit 22 also resonant to this carrier frequency and through coils 9, 7 and 8 to the line 1, 2. Voice currents directed against the microphone 12 cause variable currents to be induced in the winding 23 in the input of the modulator which voice currents cause the amplitude of the output wave to be varied in a similar manner. Transmitter T_2 may be of the same type as T_1 , but is adjusted to emit a carrier wave of different frequency from that generated by T_1 , which may be designated as carrier frequency (two). The specific transmitting equipment shown forms no part of the present invention, and any other suitable type may be used in place of the particular ones illustrated and described if desired.

Due to the symmetrical character of the coils 7, 8 and 9, and the net 5 at line 1, 2 the current introduced from coil 9 causes no potential difference to be set up between the bridging points 24 and 25 as is well known in the art. The filter F in the line is so proportioned as to pass freely currents of carrier frequency, but to attenuate and substantially extinguish currents of voice frequency, which may have found their way through the modulator directly. Also if the line 1, 2 is used to convey ordinary voice currents, together with the carrier currents, the filter F functions in preventing such currents from having access to the receivers on the line 1, 2 that are intended for the carrier current modulations. The line 1, 2 is provided with the net circuit 6 for balancing the line as to the transmitted frequencies, and with the usual conjugate coils 26 and 27, to the mid-points of which is connected the bridged coil 28 coupled to the input coil 29 of the repeater circuit. To the terminals of coil 29 are connected the respective grids 30 and 31 of the two-sided amplifier and the mid-point of the coil is connected through a polarizing source 32 to the common connection of the respective filaments 33 and 34 so that a given potential induced in coil 29 varies the potential of grids 30, 31 equally and oppositely. Space current from source 35 is supplied to the respective anodes 36 and 37 through the choke impedances 38 and 39 and the variable output currents that have been repeated pass through the path containing condensers 40 and 41 and coil 42 by which they are impressed on the outgoing line section 3, 4 through the windings 43 and 44. By means of the usual balancing net 45 these outgoing currents are prevented from producing current flow in the bridged coil 46 which is coupled to the input of the amplifier provided for repeating in the opposite direction. Currents incoming over line 3, 4, however, find their way through coil 46 and are repeated in the manner entirely similar to that described by

the currents impressed on coils 28 and 29, and after being amplified are transmitted through coil 47 and coils 26 and 27 to the line section 1, 2. The repeaters described are free from selective circuits and are adapted to amplify currents of any desired frequency, and their mode of connection with the line enables simultaneous repeating in both directions.

Receivers R_1 and R_2 are provided for operating with distant transmitting sets which may be similar in general to T_1 and T_2 . The currents incoming over line 1, 2 which may have been repeated from line 3, 4 to line 1, 2 in the manner just described will find their way in part through the bridged coils 48 and 49 and produce currents in the tuned circuits 50 and 51, which are respectively tuned to the carrier frequencies with which they are designed to cooperate. Receiver R_1 , for instance, may receive the message conveyed on current of carrier frequency (one), and R_2 may receive that conveyed on current of carrier frequency (two), or the receivers may be made to cooperate with still different carrier frequencies. Receiving set R_2 is shown as comprising a thermionic detector 52 by which the voice currents which were used to modulate the carrier wave of frequency (two) are detected and impressed upon the filter which transmits the voice frequency currents to the telephone receiver 53, but prevents the passage of frequencies higher than voice frequency which may have got through the detector. In similar manner receiving set R_1 may detect and separate out the message current conveyed on carrier current of frequency (one) and render it receivable by the telephone receiver 54. The particular type of receivers used is immaterial so far as the present invention is concerned, those described being merely for purposes of illustration.

Although the invention has been described and illustrated with reference to a specific preferred embodiment it is to be understood that it is not to be limited to the particular system as a whole or the specific details, but only to the scope of the appended claims.

What is claimed is:

1. In a carrier wave transmission system a transmission line having considerable attenuation, means for simultaneously generating a plurality of carrier waves having distinctive frequencies, means for modifying said waves simultaneously each in accordance with a different respective signal to be transmitted, a single amplifying repeater circuit for simultaneously amplifying all of said signal modified carrier waves, said amplifying repeater circuit comprising a pair of three-element space discharge devices connected in balanced relation with re-

spect to each other whereby the amplifying circuit as a whole has a substantially linear relation between impressed voltages and output current within the operating range, and 5 a single transmission path for conveying the amplified waves of the different frequencies in common into said transmission line for transmission thereover.

2. In a carrier wave transmission system 10 a long transmission line divided into sections, means for simultaneously generating a plurality of carrier waves having distinctive frequencies, means for modulating said waves simultaneously each with speech 15 variations representing a different conversation to be transmitted and for impressing the resultant modulated waves on said line, a single amplifying repeater circuit inserted between two of the sections of said line for 20 simultaneously amplifying for retransmission over a line section all of said speech modulated carrier waves received over the preceding line section, said amplifying circuit comprising a pair of three-element 25 space discharge devices connected in balanced relation with respect to each other whereby the amplifying circuit as a whole has a substantially linear relation between impressed voltages and output current with- 30 in the operating range, and means for connecting said repeating circuit to the incom-

ing and outgoing line sections, said repeating circuit and said connecting means both being free of circuits selective of the individual waves transmitted.

35

3. In a carrier wave transmission system the combination with a long line and terminal apparatus for simultaneously impressing thereon at a terminal point a plurality of carrier waves of distinctive frequencies modulated in accordance with respective conversational current variations, of an amplifying repeater circuit between the terminals of the line comprising a pair of space discharge tubes of the audion type 40 connected in balanced relation with respect to each other whereby the amplifying circuit possesses a substantially linear relation between impressed voltages and output currents, and connections for impressing a plurality of the modulated carrier waves received over a portion of said line upon the repeating circuit for amplification and for 45 impressing the waves representing said plurality of modulated carrier waves amplified 50 by said repeater circuit upon said line for transmission thereover to a distance.

In witness whereof, I hereunto subscribe my name this thirteenth day of October, A. D., 1919.

BURTON W. KENDALL.
